(57) **CLAIM**

The ornamental design for a chair, as shown and described.

DESCRIPTION

FIG. 1 is a perspective view of a chair according to this design;

FIG. 2 is a front view thereof;

FIG. 3 is a right side view thereof; the left side view being a mirror image of the left side view;

FIG. 4 is a rear elevational view thereof;

FIG. 5 is a top view thereof; and,

FIG. 6 is a bottom view thereof.

The broken lines define the bounds of the claim and form no part thereof.

1 Claim, 3 Drawing Sheets

FIG. 2

FIG. 1

FIG. 4

FIG. 3

FIG. 6

FIG. 5
